[57] CLAIM

The ornamental design for a telecommunications adaptor pod, as shown and described.

DESCRIPTION

FIG. 1 is a perspective view illustration showing the front, top, and right sides of a telecommunications adaptor pod;

FIG. 2 is a top plan view thereof;

FIG. 3 is a bottom plan view thereof;

FIG. 4 is a side elevational view thereof;

FIG. 5 is a front elevational view thereof, showing two connector ports;

FIG. 6 is a rear elevational view thereof; and,

FIG. 7 is a front elevational view of an alternative embodiment of the telecommunications adaptor pod having three connector ports.

All other views are the same as the first embodiment except for the appearance of the connector ports.
